Attorney

UNITED STATES PATENT OFFICE.

FRED NELSON, OF MANLIUS, NEW YORK.

WINDOW VENTILATOR.

Application filed November 4, 1921. Serial No. 512,794.

To all whom it may concern:

Be it known that I, FRED NELSON, of Manlius, in the county of Onondaga, in the State of New York, have invented new and useful Improvements in Window Ventilators, of which the following, taken in connection with the accompanying drawings, is a full, clear, and exact description.

This invention relates to a window ventilator as a unitary article of manufacture to be removably inserted in the sash guides between the upper sash and top of the window frame or between the lower sash and window-sill.

The main object is to provide a ventilator with a swinging hood movable to and from a position across the main ventilating opening and equipped with a ventilating screen and a closure, both hinged to swing one upon the other across the opening in the bottom of the hood to enable the ventilator to be fully opened, screened or entirely closed.

Another object is to provide opposite longitudinal edges of the main ventilating plate with guides for the reception of extensible supports which are movable into and out of engagement with the window guides.

Other objects and uses relating to specific parts of the device will be brought out in the following description.

In the drawings:

Fig. 1 is a perspective view of a window ventilator embodying the various features of my invention in which the hood and screen are adjusted for ventilating purposes, while the closure is shown as partially open.

Fig. 2 is a transverse vertical sectional view of the device shown in Fig. 1.

Fig. 3 is an enlarged detail sectional view taken on line 3—3, Fig. 2.

As illustrated, this window ventilator comprises a rectangular ventilating plate —1— preferably of sheet metal of slightly less length than the distance between the upright sides of the window frame in which it is adapted to be placed and of any suitable height, said plate being provided with a rectangular opening —2— and lengthwise guides —3— along its opposite longitudinal edges for the reception of the opposite arms

of a pair of U-shaped supporting members —4—, which are slideable or adjustable endwise along said guides to permit the entire device to be readily inserted into and removed from the sash guides of the window opening in which the ventilator is adapted to be placed.

The opening —2— is formed centrally in the major portion of the area of the plate —1— a sufficient distance within the marginal edges thereof to form a frame-work extending entirely around the opening.

The guides —3— are formed by bending the opposite longitudinal edges of the frame of the plate —1— inwardly at the same side and then downwardly and outwardly to form lengthwise grooves in which the opposite arms as —5— of the U-shaped members —4— are slideable, the out-turned edges of the guides forming flanges —6— at the inner sides of the grooves and of substantially half the width of the guides from front to rear to engage the adjacent edges of the arms of the inner U-shaped members —4— and thereby to assist in holding the arms in parallelism or against inward displacement.

The portion of the plate —1— forming the upper wall of the opening —2— is deflected outwardly and downwardly a short distance at —7— to form a water board or deflecting member for deflecting rain and snow away from the opening.

Suitable hinge members —8— are fastened by spot-welding or otherwise to the inner face of the plate —1— just above the opening —2— for receiving and supporting a hood-plate —9— which is hinged along its upper edge at —10— to the members —8— to swing inwardly and outwardly or to and from a vertical position across the opening —2— for effectively closing said opening when adjusted to its extreme inward position, it being understood that the hood-plate is also rectangular and of sufficient area to substantially cover the opening when closed, the lower edge of said hood-plate being extended to form a flange —11— which overlaps the outer face of the lower wall of the opening when the hood is in its closed position to additionally deflect rain and snow from said opening.

The ends of the hood-plate —9— are bent inwardly to form triangular end walls —12— which together with the member —9— constitutes a hood, the end walls extending downwardly from the upper edge of the plate a distance substantially equal to the vertical height of the opening —2— so as to swing in said opening close to the end walls thereof as the hood is swung inwardly and outwardly to and from its closed position.

The inner edges of the end walls —12— of the hood are provided with out-turned flanges —13— forming stops for engaging the inner faces of the end walls of the opening —2— to limit the outward swinging movement of the hood and thereby to cause the plate —9— to assume a downwardly and outwardly inclined position when the hood is opened.

Suitable buttons —14— are pivoted to the plate —1— just below and at opposite ends of the opening —2— to swing into and out of engagement with the adjacent flanges —13— of the hood to hold the latter in its extreme open position and also to release the hood to allow it to be swung inwardly to its closed position.

The object of this swinging movement of the hood is to permit it to be closed flatwise with its plate —9— approximately coincident with the plane of the plate —1— particularly where outside blinds are used, thus permitting the blinds to be closed without displacing the hood from the window or when the blinds are opened, the hood may be extended to its open position for ventilating purposes, it being understood that the lower and inner sides of the hood are opened to allow the air to pass therethrough when desired.

A rectangular screen —15— of substantially the same area as the opening in the bottom of the hood is hinged at —16— along its outer longitudinal edge to the inner face of the hood-plate —9— to swing vertically between the end walls —12— in close proximity thereto end to end from a position across the inner face of the plate —9— where it may be held by a spring catch or detent —17—, or when released may be rocked inwardly and downwardly across the opening in the bottom of the hood and into engagement with the lower wall of the opening —2—, the inner edge of the screen being provided with a flange —18— constituting a stop for limiting the outward swinging movement of the hood by contact of the inner face of the plate —1—.

A rectangular plate or closure —19— of sufficient area to cover the foraminous part of the screen —15— is hinged along its outer edge at —20— to the inner face of said screen for closing the openings therethrough but may be opened toward the

plate —9— and held in its open position by a catch —21— thereby permitting the air to pass through the screen and into the room through the opening —2— when the hood is opened or the screen —15— and closure —19— may be locked in their open positions and the hood rocked to its closed position, as shown by dotted lines in Fig. 2.

The object of the closure —19— is to close the foraminous part of the screen —15— when the hood is opened as may be necessary during temporary cold spells or excessive wind, but under ordinary conditions may be left opened for ventilating purposes.

In case blinds are used on the outside of the building and it is desired to close the same, the buttons —14— may be turned to release the hood and to allow the same to drop by its own weight to its closed position in which position, it may be locked by returning the buttons —14— to engage in notches —22— in the lower edges of the end walls —12— near the plate —9—, it being understood that the screen —15— and closure —19— will then have been opened and locked in their open positions by the catches —17— and —21—, respectively.

The opposite arms —5— of the U-shaped members —4— are recessed along their adjacent faces and overlapped one upon the other for relative sliding movement in the grooved flanges —3— so that the combined thicknesses of the adjacent arms from front to rear are substantially equal to the corresponding interior width of the grooves in the flanges —3— and also of approximately the same thickness as the remaining portions of the arms, which enable the flange members —3— to be formed of the same size throughout their lengths.

What I claim is:

1. In a ventilator having a hood open at the bottom for ventilating purposes, the combination of a screen hinged to the hood to swing to and from a position across said opening, and a closure hinged to the screen to swing to and from a position across the opening therein.

2. In a ventilator having a frame provided with an opening for ventilating purposes, and a hood hinged to swing in the opening and open at the bottom for ventilating purposes, the combination of a screen hinged adjacent the lower edge of the hood to swing to and from a position across the open bottom thereof, and a closure plate hinged to the screen to move to and from a position across the openings therein.

3. In a ventilator having a frame provided with an opening for ventilating purposes and a hood hinged to swing in the opening and open at the bottom for ventilating purposes, the combination of a screen hinged adjacent the lower edge of the hood to swing to and from a position across the

open bottom thereof, a closure plate hinged to the screen to move to and from a position across the openings therein, means for holding the hood in its open position, means on the hood for holding the screen in its open position, and means for holding the closure plate in its open position, said frame being provided with relatively mov-

able end extensions for varying the effective length thereof. 10

In witness whereof I have hereunto set my hand this 29th day of October, 1921.

FRED NELSON.
